(57) **CLAIM**

The ornamental design for an equipment holder, as shown and described.

DESCRIPTION

FIG. 1 is a perspective view of an equipment holder;
 FIG. 2 is a front view thereof;
 FIG. 3 is a back view thereof;
 FIG. 4 is a first side view thereof;
 FIG. 5 is a second side view thereof;
 FIG. 6 is a top view thereof;
 FIG. 7 is a bottom view thereof; and,
 FIG. 8 is another perspective view of an equipment holder, in an opened state.
 The dashed lines depict portions of the equipment holder that form no part of the claimed design.
